UNITED STATES PATENT OFFICE.

OLIVER L. BADGER, OF PLAINFIELD, NEW JERSEY, ASSIGNOR TO KERR ADJUSTABLE STRAP COMPANY, INC., OF NEW YORK, N. Y., A CORPORATION OF NEW YORK.

FLEXIBLE SUPPORT.

1,309,605.

Specification of Letters Patent.

Patented July 15, 1919.

Application filed August 29, 1918. Serial No. 251,897.

To all whom it may concern:

Be it known that I, OLIVER L. BADGER, a citizen of the United States, and a resident of Plainfield, in the county of Union and State of New Jersey, have invented a new and useful Improvement in Flexible Supports; and I do hereby declare the following to be a full, clear, and exact description thereof.

10 My invention pertains to adjustable flexible supports, such as gun slings, stirrup straps, etc., and has for its principal object the provision of a support of the above general class that may be readily adjusted to different lengths, or disassembled altogether, and one in which the possibility of accidental change of adjustment will be reduced to a minimum.

Another object is the provision of a support 20 that will utilize friction locking buckles instead of the common form of prong buckle which weakens and wears the support.

In the accompanying drawings I have shown a support constructed according to 25 my invention as being in the form of a gun sling. However, it will be understood that the same support may be used for different purposes, all of which are to be understood as part of the present invention.

30 Figure 1 is a side view of the support as used on a gun;

Fig. 2 is a front view of the same; and

Fig. 3 is a perspective view of the buckle.

Referring now particularly to the drawings, the form of support shown therein 35 comprises a flexible member or strap 2 having snap hooks 3 and 4 secured at its respective ends, and having a buckle A of the friction type mounted thereon. The buckle 40 A comprises a body plate 5 having a slot 6 formed therein and having a friction clamping tongue 6' pivotally mounted on side portions 7.

The support is adapted to be mounted on 45 fittings or links 8 and 9 on the gun 10, and is capable of adjustment without disengaging it from such fittings.

The snap hook 3 is secured to the fitting 8 and the other end of the strap 2 is threaded 50 through the other fittings 9 forming portion or lap 11, and turned back then threaded through the slot 6 in the buckle A forming lap 12, and then through between laps 11 and 12 forming lap 13 and secured by snap hook 4 to fitting 9.

By releasing the clamping tongue 6' and moving the buckle to or from the snap-hook 3 the support may be shortened or lengthened as will be readily apparent.

It will be obvious when my improved flexible support is in use with some forms of guns, such as the Browning gun, that suitable means, such as keepers preferably formed of metal, can be applied to the arm loop of the support for holding the loop up 60 on the arm in case the gun is fired from the shoulder.

While the support described above has been referred to in its use as a gun sling, it can be used in many other instances where 70 adjustable and flexible supports are desired, and various changes in design and construction may be made by those skilled in the art without departing from the spirit of my invention as defined in the following claims: 75

1. In a flexible support, a link, a strap detachably secured at one end to said link and extended from said link to a point, then passed through a second link and returned upon itself forming a loop and extending to 80 a point short of said first named link, thence passing through a friction buckle detachably mounted on said strap, thence returning upon itself and detachably secured to said second named link. 85

2. In a flexible support, a link, a strap detachably secured at one end and to said link and extended from said link to a point, thence passed through a second link and returned upon itself forming a loop and extending to 90 a point short of said first named link, thence passing through a friction buckle detachably secured to said strap, thence returning within said loop and being secured to said second named link. 95

3. The combination with a gun stock, of a sling comprising a strap having its one end secured to a fitting on the butt of said gun, and extending from said fitting to a point, thence passing through a second fitting and returning upon itself forming a loop and extending to a point short of said first named fitting, thence passing through a friction buckle detachably secured to said strap, thence returning within said loop and secured to said second named fitting. 100

4. The combination with a gun stock, of a sling comprising a strap having snap hooks secured to each end, one of said snap hooks being detachably secured to a fitting on the 110

body of a gun, said strap extending from said fitting to a point, thence passing through a second fitting and returning upon itself forming a loop and extending to a point short of said first named fitting, thence passing through a friction buckle slidably mounted upon said strap, thence returning within said loop and detachably secured by the other of said snap hooks to said second named fitting.

5. In a flexible support, a link, a strap having snap hooks secured to each end, said strap having its one end secured to said link by one of said snap hooks and extending from said link to a point; thence passing a

second link and returning upon itself forming a loop and extending to a point short of said first named link, thence passing through a friction buckle slidably mounted upon said strap, thence returning within said loop and detachably secured to said second named link by means of the other of said snap hooks. 20

In testimony whereof, I the said OLIVER L. BADGER, have hereunto set my hand.

OLIVER L. BADGER.
